ABSTRACT OF THE DISCLOSURE

A method for improving the air oxidation of hydrocarbons to their corresponding alcohols by adding dried boric acid to liquid hydrocarbon in an air oxidation reactor by delivering the boric acid from a collecting container to an intermediate container and from there through a pocket wheel to be carried by an inert gas through a dip tube immersed in the hydrocarbon.

CROSS-REFERENCE TO RELATED APPLICATIONS

Applicant claims priority under 35 U.S.C. 119 for application Ser. No. 43,804 IVb/12 filed in the Patent Office of the Federal Republic of Germany on Nov. 10, 1967.

BACKGROUND OF THE INVENTION

The field of the invention is air oxidation of hydrocarbons to their corresponding alcohols.

The state of the prior art is set forth in British Pat. 1,069,733; French Pat. 1,445,874; and U.S. Pat. 3,287,423 of Steeman et al.

Steeman et al. disclose the improvement of the process of preparing cyclic alcohols by the air oxidation of hydrocarbons, having a suspension of boric acid therein, by mixing the hydrocarbons with an aqueous solution of boric acid and then evaporating all the water from the mixture to leave behind a suspension of solid boric acid in hydrocarbons.

In the method disclosed in British Pat. 1,069,733, the boric acid solution resulting from the hydrolysis of boric acid ester is dehydrated in the presence of the hydrocarbon being oxidized. The process is carried out in two stages with the aid of an azeotropic distillation. When carrying out the method according to the British patent, the impurities dissolved in the water are not removed and are returned to the oxidation step.

It is particularly difficult to deliver dried boric acid into the oxidation chamber because the normal conveyor means like pumps or twin screw conveyors are subjected to considerable wear due to the hardness of the dried boric acid.

It is not possible to employ a hydrocarbon such as cyclododecane for conveying the dried boric acid because of the high melting point of cyclododecane. If the cyclododecane is warmed above the melting point and boric acid is dissolved therein, then it is necessary to provide for the control of the considerable vapor pressure which results.

Since a mixture of dried boric acid and liquid cyclododecane solidifies to a hard mass which easily clogs the means of conducting, this fact must be taken into consideration. Considerable expense is required to clear conduits which are clogged with a hard mass of solidified boric acid and cyclododecane.

French Pat. 1,445,874 teaches the introduction of a

2

boric acid water solution, or preferably a water moist boric acid, into the hydrocarbon oxidation reactor by means of a dip tube immersed in the hydrocarbon. The process of oxidation is disturbed because of the water which is introduced with the boric acid. When the boric acid is introduced into the reactor through the dip tube by means of air pressure, a part of the boric acid is blown out of the reactor resulting in the clogging of the exhaust gas channels. The boric acid is blown out because of the amount of air and the pressure required to introduce the boric acid. Thereafter, the boric acid lost cannot provide the protective esterification needed and because of the entrained boric acid in the gas chamber of the reactor, the exhaust gas channels become clogged. The air used to introduce the boric acid precipitates the reaction in an uncontrolled manner.

It is not feasible to introduce the air carrier at the same time as the oxidation air because the oxidation air must be introduced into the reactor in a very fine distribution. Even if inert gases are employed in place of the air carrier, the same disadvantages exist.

SUMMARY OF THE INVENTION

It is therefore an object of the present invention to introduce dried boric acid into liquid hydrocarbon during the air oxidation to the corresponding alcohols by using a dip tube immersed in hydrocarbon.

According to the present invention the oxidation of the hydrocarbon in the presence of boric acid is interrupted and the resulting boric acid ester is saponified to yield a saturated boric acid solution in admixture with the products of oxidation. The boric acid solution is separated from the product and the boric acid crystallizes from the saturated boric acid solution. The boric acid is processed in the usual manner, cleaned, dried and transported into a collecting container.

It has been found that the disadvantages of the prior art can be avoided if the boric acid which is separated and dried from the hydrolysis step of the boric acid ester, is first transported from the collecting container to an intermediate container, and then from the intermediate container is delivered by a known sluice installation and an inert gas under pressure into a dip tube immersed in the hydrocarbon.

A pocket wheel has proved to be particularly advantageous as the sluice installation.

BRIEF DESCRIPTION OF THE DRAWING

The drawing appended hereto is a diagrammatic representation of the apparatus used in carrying out the process.

The improvement of the present invention is described by reference to the drawing. From a silo 1 the boric acid is delivered over a metering-belt scale 2 and through an injector 3 to the cyclone 4. The boric acid falls into the intermediate chamber 5. A pocket wheel 6 delivers it to the dip tube 9 and into the reactor 8. A current of nitrogen flows through conduit 7 into the dip tube 9. Conveyor air from the injector 3 escapes through the conduit 10. The dispersion of boric acid in hydrocarbon is agitated by stirrer 11 and air is introduced by nozzle 12.

DESCRIPTION OF THE PREFERRED EMBODIMENTS

Hydrocarbons found particularly suitable for use in the present oxidation process are saturated aliphatic hydrocarbons containing at least 10 carbon atoms and cycloaliphatic hydrocarbons containing at least 6 carbon atoms, and mixtures thereof. That is to say, any non-aromatic hydrocarbon can be oxidized in liquid phase under the reaction conditions.

Examples of suitable cycloaliphatic hydrocarbons include cyclohexane, cycloheptane, cyclooctane, cyclononane, particularly cyclodecane, cycloundecane and cyclododecane. Also polycyclic cycloaliphatic hydrocarbons, e.g. perhydronaphthalene and unsaturated cycloaliphatic hydrocarbons, e.g. tetrahydronaphthalene can be used.

Aliphatic hydrocarbons can be, for example, decane, undecane, dodecane, tridecane and tetradecane. Also branched chain isomers of the precedingly described saturated aliphatic hydrocarbons and also unsaturated aliphatic hydrocarbons can be used.

Because of the intermediate containers a sufficient density of the boric acid anhydride is achieved on the side opposite to the entrance to the reactor.

It is to be expected that hydrocarbon vapors such as cyclododecane vapors would form deposits with the boric acid to clog the sluice installation, but because of the cooperation between the intermediate container and the sluice installation, the boric acid is introduced into the reactor without difficulty.

As the inert gas, nitrogen is delivered under excess pressure through the dip tube immersed in the hydrocarbon. The excess pressure is dependent upon the immersion depth of the tube and upon the throttling of the exhaust gas path. The usual excess pressure of the inert gas amounts to about 0.1 to 0.2 atmospheres absolute.

This pressure is sufficient to overcome the minor excess pressure present in the reactor and therefore avoids the syphoning action of cyclododecane in the dip tube.

The nitrogen is usually introduced in amounts of about 100-500 litres per hour.

The immersion tube is continuously rinsed with small amounts of inert gas through injector 7, and this rinsing continues during the filling and draining of the hydrocarbon oxidation reactor.

Dried boric acid is advantageously removed from silo 1 under conditions of fluidized air with the aid of an injector via a measuring device, such as a metering-belt scale into the intermediate container. The intermediate container 5 is advantageously located above the hydrocarbon oxidation reactor 8.

By carrying out the process according to the present invention, it is possible to remove all of the air used for fluidizing the product in the silo.

The intermediate container is connected by a sluice installation to the dip tube immersed in the hydrocarbon. The sluice installation is preferably a rotary vane feeder. A constant stream of nitrogen of about 100-500 liters per hour is blown into the dip tube through conduit 7 and this prevents cyclododecane vapors from rising into the path of the descending dried boric acid.

The dried boric acid can be carried from the intermediate container to the site of the oxidation reaction in a continuous or in a discontinuous manner. As dried boric acid especially is used meta-boric acid. Also ortho-boric acid may be used. Boric acid anhydride is less suitable for the reaction.

Without further elaboration, it is believed that one skilled in the art can, using the preceding description, utilize the present invention to its fullest extent. The following preferred specific embodiments are, therefore, to be construed as merely illustrative, and not limitative of the remainder of the specification and claims in any way whatsoever.

EXAMPLE 1

Comparative example

An agitated vessel having a 20 cubic meter capacity is charged with 12,000 kilograms of cyclododecane feed in about one hour at 150-180° C. There are also charged to the reactor over a span of about 4-5 hours 400 cubic meters per hour of air of which about 80% of the oxygen therein is consumed during the oxidation reaction. In addition, 100 kilograms per hour of meta-boric acid are continuously pneumatically added by means of a dip tube

immersed in the cyclododecane to the oxidation mixture during the course of the reaction. After a conversion of 30%, the oxidation reaction is interrupted and the resulting boric acid ester is thereafter saponified at 90° C. with 2200 litres of water to yield a saturated boric acid solution in admixture with the products of oxidation. After separating the boric acid solution (lower layer) from the product (upper layer), the latter product is then purified in a conventional manner by fractional distillation thereof. The yield of cyclododecanol/one is 80.5 mole percent of theoretical based on the reacted hydrocarbon. During the reaction the dip tube is often clogged by the boric acid. Therefore the reaction must be interrupted and the dip tube must be cleaned.

EXAMPLE 2

(Demonstrating the invention)

Example one is repeated. In place of the dip tube immersed in the cyclododecane, the apparatus according to 20 the invention is used. A silo contains the dried meta-boric acid. The boric acid is transferred to an intermediate container, then removed from said intermediate container in incremental portions by a pocket wheel and delivered said incremental portions of boric acid by a flow of an inert 25 gas (nitrogen) under an excess pressure of 0.1 to 0.2 atmospheres (about 100 to 500 litres per hour) through said dip tube immersed in the cyclododecane. The yield of cyclododecanol/one is 80.5 mole percent of theoretical based on the reacted hydrocarbon. The dip tube is not clogged by the boric acid, and the time to carry out the 30 reaction is shortened. No cleaning step and no interruption of the reaction is necessary.

The preceding examples can be repeated with similar 35 success by substituting the generically and specifically described reactants and operating conditions of this invention for those used in the preceding examples.

From the foregoing description, one skilled in the art 40 can easily ascertain the essential characteristics of this invention, and without departing from the spirit and scope thereof, can make various changes and modifications of the invention to adapt it to various usages and conditions.

What is claimed is:

1. In the method of air oxidation of non-aromatic hydrocarbons to their corresponding alcohols by introducing boric acid into an aerated liquid phase, non-aromatic hydrocarbon selected from the group consisting of saturated aliphatic hydrocarbons containing at least 10 carbon atoms and cycloaliphatic hydrocarbons containing at least 6 carbon atoms, and mixtures thereof whereby hydrocarbyl esters of the boric acid are formed, saponifying the esters formed, separating and drying the boric acid and reintroducing said boric acid to the oxidation step, the improvement comprising:
  - (a) introducing the dried boric acid into a collecting container; and
  - (b) delivering said boric acid under the force of gravity under an enveloping continuous flow of inert gas through a dip tube immersed in said non-aromatic hydrocarbon located in an oxidation zone, said inert gas being maintained continuously at a positive pressure with respect to the pressure of the reactor, whereby said non-aromatic hydrocarbon is hindered from passing up into the tube.
2. A method as defined by claim 1, further comprising the intermediate steps of:
  - transferring the boric acid from the collecting container to an intermediate container, and removing the boric acid from the intermediate container in incremental portions.
3. A method as defined by claim 2 wherein said intermediate container is disposed above the dip tube.
4. A method as defined by claim 1, further comprising introducing air through a nozzle immersed in said hydrocarbon in the same oxidation zone wherein said boric acid is fed through said dip tube.

5. A method as defined by claim 4, said dip tube being continuously rinsed by said inert gas during the filling and draining of the oxidation reactor.

6. The method of claim 1, wherein said hydrocarbon is cyclododecane.

7. The method of claim 3, wherein said incremental portions are delivered by a rotary vane feeder.

8. A method as defined by claim 7 wherein boric acid is fed through said rotary vane feeder into the top of said dip tube and wherein inert gas is fed into said dip tube at a position downstream of said rotary vane feeder.

9. The method of claim 1, wherein said inert gas is nitrogen.

10. In the method of air oxidation of non-aromatic hydrocarbons to their corresponding alcohols by introducing boric acid into an aerated liquid phase, non-aromatic hydrocarbon selected from the group consisting of saturated aliphatic hydrocarbons containing at least 10 carbon atoms and cycloaliphatic hydrocarbons containing at least 6 carbon atoms, and mixtures thereof whereby hydrocarbon esters of the boric acid are formed, saponifying the esters formed, separating and drying the boric acid and introducing said boric acid to the oxidation step, the improvement comprising:

(a) gravity feeding the dried boric acid into a dip tube immersed into said non-aromatic hydrocarbon located in an oxidation zone; and

(b) simultaneously and continuously passing an inert gas into said dip tube to envelop said boric acid, said inert gas being continuously maintained at a positive pressure with respect to the reactor, whereby said non-aromatic hydrocarbon is prevented from passing up into the dip tube.

11. The method of claim 10, wherein said hydrocarbon is cyclododecane.

12. The method of claim 10, wherein said inert gas is nitrogen.

13. The method of claim 10 wherein said inert gas is maintained at a positive pressure of about 0.1-0.2 atmospheres absolute with respect to the reactor.

14. A method as defined by claim 13, inert gas being introduced into said dip tube at a position below the introduction of boric acid into the dip tube.

15. A method as defined by claim 10, further comprising introducing air through a nozzle immersed in said hydrocarbon in the same oxidation zone wherein said boric acid is fed through said dip tube.
